Primary Examiner — Marianne Pandozzi*(74) Attorney, Agent, or Firm* — JoAnn M. Seaton; Griffiths & Seaton PLLC(57) CLAIM

The ornamental design for Halloween themed serveware, as shown and described.

DESCRIPTION

FIG. 1 is a top front perspective view of Halloween themed serveware showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top and front perspective view of the Halloween themed serveware of FIG. 1 shown with additional unclaimed subject matter;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

In the drawings, the broken lines depict unclaimed subject matter only and form no part of the claimed design. The features shown in long dash-short dash bolded broken lines indicate the bounds of the claimed design and otherwise form no part of the claimed design.

1 Claim, 14 Drawing Sheets(56)
